UNITED STATES PATENT OFFICE.

RUFUS A. PARENT, OF TACOMA, WASHINGTON.

ADJUSTABLE MEASURING-SCOOP.

1,324,264.

Specification of Letters Patent.

Patented Dec. 9, 1919.

Application filed May 31, 1919. Serial No. 300,801.

To all whom it may concern:

Be it known that I, RUFUS A. PARENT, a citizen of the United States, residing at Tacoma, in the county of Pierce and State 5 of Washington, have invented certain new and useful Improvements in Adjustable Measuring-Scoops, of which the following is a specification, reference being had therein to the accompanying drawings.

10 This invention relates to an adjustable measure-scoop for teas, coffees, and any powdered substance, and the object of the invention is the construction of a simple and efficient scoop or scoop-like measurer 15 which will be comparatively inexpensive to manufacture.

Another object of the invention is the construction of a scoop of a simple structure that will be easy to handle and manipulate, and which can be readily assembled 20 during the manufacture thereof.

With these and other objects in view, my invention comprises certain novel constructions, combinations, and arrangements of 25 parts as will be hereinafter specifically described, illustrated in the accompanying drawings, and more particularly pointed out in the appended claims.

In the drawings, 30 Figure 1 is a perspective view of the measure or scoop constructed in accordance with the present invention.

Fig. 2 is a view in side elevation of the measure-scoop.

35 Fig. 3 is a sectional view taken on line 3—3, Fig. 1.

Fig. 4 is a sectional view taken on line 4—4, Fig. 2, looking in the direction of the arrows.

40 Fig. 5 is a plan view of the blank from which the adjustable slide is formed.

Fig. 6 is an enlarged, fragmentary view 45 of another embodiment of the measure-scoop.

45 Referring to the drawings by numerals, the body or receptacle of the measure-scoop is preferably of an oblong structure, and comprises a flat bottom 1, sides 2, and an inclined or scoop end 3; the opposite end 50 of the receptacle is closed by the handle 4, which handle is preferably formed of wood for cheapening the expense of manufacture, and the handle is fastened in the open end of the receptacle by any suitable fastening means as, for instance, tacks or pins 5; the handle 4 efficiently closes the open end of

the body, and the handle, when assembled with the receptacle, constitutes a part thereof.

Integral with the upper edges of the 60 sides 2 are horizontal, outwardly-extending flanges 6.

The slide is formed from a single piece of metal, and comprises a finger-engaging, flat portion 7 with a tongue 8; integral with 65 the flat portion 7 are flange portions 9, and integral with these flange portions 9 are pointed indicators 10. The flange portions are folded along the dotted lines 11, and the indicators 10 are also folded along the 70 dotted lines 12. When the blank is folded, the tongue 8 extends downwardly (Figs. 1 and 3) and the flange portions 9 overhang and partly surround the flanges 6 on the sides 2 (Figs. 4), and the indicators 10 are 75 positioned parallel with the sides 2. The slide is mounted upon the flanges 6 before the handle 4 is placed between the sides and fastened; to remove the slide, all that is necessary is to remove the pins or tacks 5, 80 detach the handle 4, and then the slide can easily be slid off the receptacle.

Any suitable graduation or measuring marks, as marks 13, can be placed upon the sides for designating quantities of material 85 to be measured by this measure-scoop; in the particular illustration in Figs. 1 and 2, I have shown markings for indicating tea-spoonfuls and tablespoonfuls of tea or coffee, and it will be readily understood that 90 when the indicators 10 are contiguous to certain markings as shown, certain proportions of coffee or tea or the like will be measured by this scoop, at the will of the operator.

In the embodiment shown in Fig. 6, the flanges 6^a are provided with outer toothed or serrated edges 6^b, and the flange portions 9^a of the slide are depressed or indented at 9^b to cause a binding action of the slide 100 upon the toothed or serrated edge 6^b of the flanges 6^a for holding this slide in an adjusted position against accidental displacement, whereby it will not be necessary for the operator to press upon the 105 slide during the handling or measuring of materials or foods, as is the case with the slide shown in Figs. 1 to 4. The binding action in this embodiment of the slide upon the flanges 6^a is not so great as to cause an 110 undue effort to adjust the slide by the operator, but is just sufficient to lock or retard

the slide against accidental displacement after it has been adjusted for measuring a given quantity.

It will be understood from the foregoing description illustrating the two embodiments of my invention, that certain minor alterations or changes may be made in the manufacture of my measure-scoop, and, therefore, I reserve the right to make such minor alterations or changes as shall appear to one skilled in the art to which this invention relates, and which fairly fall within the scope of the appended claims.

What I claim is:

- 15 1. In a device of the class described, the combination of a receptacle including in one end a handle and having at its opposite end an inclined scoop-end, and a slide provided with a depending tongue upon the receptacle and movable between the inclined scoop-end and the handle-end.
- 20 2. In a device of the class described, the combination of a receptacle having a handle formed for closing one end and an inclined scoop-like end opposite the handle, and a movable slide for measuring carried by the receptacle between its ends.
- 25 3. In a device of the class described, the combination of a receptacle provided with sides, said sides provided with flanges, a slide mounted upon said receptacle and provided with flange portions surrounding the flanges of the sides of the receptacle, indicators extending from said flange portions parallel with the sides of the receptacle, and said slide including a depending tongue extending into the receptacle.
- 30 4. In a device of the class described, the combination of a receptacle provided with sides, said sides provided at their upper edges with horizontal, outwardly-extending flanges, and a slide provided with a depending tongue extending into the receptacle, said slide mounted upon said flanges and having portions partly surrounding the same, and with depending indicators parallel with the sides.
- 35 5. In a device of the class described, the

combination of a receptacle provided with parallel sides, said sides provided with horizontal, outwardly-extending flanges at their upper edges, a slide formed from a single piece of metal and including a flat finger-engaging portion and an inclined tongue, said finger-engaging portion resting upon the flanges of the sides and said tongue extending down between the sides of the receptacle, said slide also provided with flanges surrounding the first-mentioned flanges, and the last-mentioned flanges provided with integral, depending indicators parallel with the sides of the receptacle.

6. In a device of the class described, the combination of a receptacle, a slide mounted upon said receptacle, and said slide provided with indicators parallel with the outer faces of the sides and with an inclined tongue extending into the receptacle between the sides.

7. In a device of the class described, the combination of a receptacle provided at its upper edges with flat flanges, a slide provided with a flat, finger-engaging portion and with an inclined tongue extending into the receptacle slidably mounted upon said flanges, said flat portion of the slide being provided with flanges at its ends partly surrounding the first-mentioned flanges, and said last-mentioned flanges on the flat portion provided with integral, depending indicators.

8. In a device of the class described, the combination of a receptacle provided with flanges having toothed or serrated edges, a slide provided with a depending tongue extending into the receptacle, said slide mounted upon said flanges and provided with flanges partly surrounding the first-mentioned flanges, and said flanges of the slide provided with means for engaging the toothed or serrated flanges of the receptacle for locking the slide in an adjusted position against accidental displacement.

In testimony whereof I hereunto affix my signature.

RUFUS A. PARENT.
